ABSTRACT

A deflection safety control for the platform of a scissors lift comprises a pendulum mounted on the platform and having a switch actuated by a part of the pendulum extending above the pivot point.

DEFLECTION SAFETY CONTROL FOR PLATFORM OF VERTICAL RISING LIFT

BACKGROUND AND SUMMARY OF THE INVENTION

Vertical lifts comprising a platform raised and lowered by a suitable power means are employed for many applications. Some of these would perhaps be classed as "elevators" while others might be called "dock lifts," etc. In many instances the motive power device is not one that would absolutely ensure that the platform remain level under all conditions of loading. For example the motive power device might be a hydraulic ram centered under the platform. Another example might be the so-called "scissors lift" commonly employed for dock lifts or the like, particularly where the lift is adapted to be moved from one location to another. While these lifts are made more than adequately strong for their intended purpose, it is possible that they can be abused in a manner such that the platform tends to tip to one side to an extent that the power device, etc., is damaged and perhaps even creating a dangerous situation so far as the workers involved are concerned. For example, there have been occasions when a scissors type dock lift was carelessly operated in a manner such that, as the platform was being raised to unload a truck, a side of the platform was caught under the truck. Since the situation was not noticed by the operator, the operator continued to endeavor to raise the lift, the result being that the platform was canted to such an extent that structural damage resulted. It is not inconceivable that a similar situation could occur as a result of excessive uneven loading of objects being supported on the platform. With a hydraulic ram type lift, such excessive uneven loading can cause deflection in the ram and damage to the bearing about the ram.

The present invention relates to a simple and effective control for use with the platform of a vertically moving lift to prevent the lift from being operated under conditions creating excessive deflection of the platform.

Utilizing the present invention the power movement of the lift is shut off when excessive deflection occurs. Thus, using the example previously given, if the platform of the dock lift were caught under a truck, the operator would be unable to further raise the platform after a predetermined degree of deflection had occurred. If such a lift resting on the floor were unevenly loaded to an extent such that excessive deflection and damage could result, the power apparatus could initially be actuated to start raising the lift, but as soon as the lift were raised sufficiently to allow deflection in excess of the predetermined amount to occur, the power operation would be shut down. Just what is excessive deflection will be determined with regard to the particular lift being protected. For example, in the dock lift hereinafter discussed, upon reaching a 6 inch deflection in one side of the platform the elastic limit will be reached and structural damage will occur. Therefore the safety device is set to prevent operation beyond the point at which a three inch deflection occurs. Provision is made in accordance with the present invention so that this determination can, if desired, be made empirically by the field adjustment of the amount of deflection that will occur before the power is shut off.

An important advantage of this invention is the simplicity of its embodiments — as compared to alterna-

tive devices (e.g. strain gauges) that might be used. It is a very simple matter to connect these embodiments into each of the variety of control circuits that might be employed with various types of lifts.

DESCRIPTION OF THE DRAWINGS

FIG. 1 is a perspective view of a lift embodying the invention;

FIG. 2 is an enlarged side view of the embodiment incorporated in FIG. 1; and

FIG. 3 is a front view as seen at line 3—3 of FIG. 2.

DESCRIPTION OF SPECIFIC EMBODIMENT

The following disclosure is offered for public dissemination in return for the grant of a patent. Although it is detailed to ensure adequacy and aid understanding, this is not intended to prejudice that purpose of a patent which is to cover each new inventive concept therein no matter how others may later disguise it by variations in form or additions or further improvements.

For the purposes of illustration, a scissors type dock lift is illustrated. This comprises a base 10, a platform 11 having ramps 12 thereon. Connecting the base and the platform are a pair of scissors devices 13, each scissors device being positioned at a respective side (of a pair of opposite sides) of the platform. The vertical movement is achieved by a pair of hydraulic rams 14 interconnecting the base and the frame of the platform 11. A hydraulic pump, etc., not shown, is connected to the rams 14 and is controlled by a suitable set of controls 15. The platform 11 includes as a part of its frame structure a housing positioned at one end of the platform and having a wall 16 transverse to the sides at which the scissors devices 13 are located. The hydraulic apparatus and controls are mounted in the housing. As thus far described, the structure represents known apparatus upon which the present invention is an improvement.

The illustrated embodiment of the present invention comprises a frame 20 secured within the housing as by means of bolts 21 and positioned between the two sides at which the scissors devices 13 are located. Pivotedly mounted on this frame is a pendulum, generally 22, which operates a control switch, generally 23. The pendulum comprises a rod 25 formed about an axis 26. Intermediate its ends it is pivotally mounted on a bolt 27 secured to frame 20, the bolt defining a pivotal axis intersecting wall 16. A suitable antifriction bearing 28 is provided on the bolt. The lower end of the rod 25 is secured to a weight 29. The upper end of the rod has a surface in the form of a shallow "V" symmetrical with respect to axis 26 (i.e., each side is a mirror image of the other).

The switch 23 includes a body 32 secured to frame 20 by four bolts 33. Provision is made so that there can be vertical adjustment of the switch 23 with respect to the pendulum 22 or vice versa. In this embodiment, such provision takes the form of slots 34 in frame 20 through which slots the bolts 33 extend. This permits the bolts 33 (and the switch body 32) to be moved vertically on the frame. When the bolts 33 are tightened, the switch 23 remains in that position.

In actual practice, the mechanism of switch 23 would comprise a snap-action switch, represented by those sold under the trademark Microswitch, however, for the purposes of illustration, merely a pair of switch

contacts 37 are shown. This switch has an actuating member in the form of a plunger 35 with a wheel 36 on the distal end thereof to move the upper contact with respect to the lower contact when the plunger is moved. As indicated by the dotted line 38, this switch is connected to the controls for the hydraulic system 15 so as to shut down the operation of hydraulic cylinders 14 in the event of excessive deflection of platform 11.

For example, assume that the near right side of platform 11 as viewed in FIG. 1 (it would be the right hand side as viewed in FIG. 3 if one could see it) is excessively loaded so that that side of the platform is substantially lower than the opposite side of the platform. This would cause the pendulum to move so that the rod assumed the position illustrated at 25' in FIG. 3. The result would be that the surface on the upper end of the rod would act as a cam and the wheel 36 act as a cam follower to move the plunger 35 upwardly, causing switch contacts 37 to open. Thereupon the controls 15 would prevent further movement of the hydraulic rams 14. Were the uneven loading to occur at the opposite side of platform 11, the rod of the pendulum would assume the position indicated at 25" and the same result would occur, namely the shutting down of the hydraulic rams 14. In any event, when the uneven loading is corrected, the pendulum 22 would move sufficiently back toward its vertical position to permit switch contacts 37 to close so that the operation of the hydraulic rams 14 can be resumed. By adjusting the spacing of the switch with respect to the pendulum, one can vary the amount of movement of the pendulum required to actuate the switch.

From the foregoing description, obvious variations will be apparent to those skilled in the art. For example, the switch 23 could be a normally open switch rather than the normally closed switch and the contacts then closed by the tipping of the pendulum. The end 30 of the rod could be an inverted "V," or even a segment of a cylinder, rather than the shallow upright "V" as illustrated and described.

In a specific embodiment employed with a dock lift as illustrated, the total length of the pendulum was 29 inches, the pivot axis (bolt 27) was 4½ inches from the nearest part of the end 30. The angle between the two sides of the end 30 was 140°. The switch 23 was a 45 Square D, type B51D.

I claim:

1. In a hydraulically powered vertical lift having a platform structure which may be unevenly loaded to an extent sufficient to damage the structure, which lift has hydraulic control means, the improvement comprising the combination with said lift of:

a frame mounted on said structure;

a pendulum device pivotally mounted on said frame for pivotal movement about an axis whereby deflections of the lift cause the pendulum device to move through angles which are a function of the extent of deflection;

control switch means operatively connected to said device to be actuated by a movement of the pendulum device through a predetermined angle; and means connecting the control switch means and the hydraulic control means to deactivate the application of hydraulic power when said control switch means is so actuated.

2. In a vertical lift as set forth in claim 1, wherein the platform has two opposite sides and an end and a wall at said end transverse to said sides, said lift including scissors means at said sides respectively, said device being mounted on said wall with said axis intersecting said wall.

3. In a vertical lift as set forth in claim 1, wherein said device includes an upright rod having an axis, a weight at the lower end of the rod, and a pivotal mounting on said axis intermediate the ends of the rod, the upper end of the rod having portions at each side of the axis which are mirror images of each other and are at different distances from the pivotal mounting than is the distance along said axis to the pivotal mounting;

said switch means having an actuating member in contact with said upper end of the rod, said actuating member being movable toward and away from said pivotal mounting to actuate the switch means.

4. In a vertical lift as set forth in claim 3, wherein one of the said switch means and the pivotal mounting is movable with respect to the other so that an adjustment may be made as to the size of said predetermined angle required to actuate the switch means.

5. In a vertical lift as set forth in claim 3, wherein said upper end is in the form of a shallow "V."
